UNITED STATES PATENT OFFICE.

WALTER ALLEN, OF WASHINGTON, DISTRICT OF COLUMBIA.

DESIGN FOR A DRAWING SUPPORT AND CARRIER.

SPECIFICATION forming part of Design No. 27,143, dated June 1, 1897.

Application filed April 29, 1897. Serial No. 634,474. Term of patent 14 years.

To all whom it may concern:

Be it known that I, WALTER ALLEN, a citizen of the United States, and a resident of the city of Washington, in the District of Columbia, have invented and produced a new and original Design for a Drawing Support and Carrier, of which the following is a specification.

My invention relates to a design for a drawing-board support or carrier for the use of draftsmen, specification-writers, and examiners whereby one or more sheets of drawing may be readily and loosely secured thereto, copied, kept flat, and handled or carried, and corrections or changes noted thereon without the liability of the drawing sustaining irreparable injury while it is in use.

The object of my invention is to provide a simple holder for the preservation of drawings while being copied, described, or examined, and thus avoid the disfigurement or mutilation of the same while in use, which has been the cause of much unnecessary and useless expense to inventors and their attorneys and also cause of delay in the prosecution of applications.

In order that my invention may be fully understood, I will proceed to describe it with reference to the accompanying drawings, in which—

Figure 1 is a perspective view of a drawing-board support or carrier, showing my new design. Fig. 2 is a longitudinal section of the same.

As shown in the drawings, the leading or 35 material feature of my design for a drawing support or carrier consists in a flat board or plate formed with a U-shaped or grooved lipping at a side thereof, having an inclined or beveled edge.

In the drawings I show a board or plate having a U-shaped or grooved lipping at one of its sides. At the side where the lipping is located the edge is inclined or beveled, thus providing a bearing or flat footing when the 45 support or carrier is set up for use. For holding the article in elevated position it may be readily placed against any convenient object.

Having thus described my invention, the following is what I claim as new therein and 50 desire to secure by Design Letters Patent:

The design for a drawing support or carrier, substantially as herein shown and described.

WALTER ALLEN.
